UNITED STATES PATENT OFFICE.

GILBERT C. WATERS, JR., OF NEW YORK, N. Y., ASSIGNOR TO SCHUYLER F. COHEN, OF BROOKLYN, NEW YORK.

WREATH AND METHOD OF MAKING THE SAME.

Application filed August 15, 1923. Serial No. 657,513.

To all whom it may concern:

Be it known that I, GILBERT C. WATERS, Jr., a citizen of the United States, and a resident of New York, in the county and State of New York, have invented certain new and useful Improvements in Wreaths and Methods of Making the Same; and I do hereby declare the following to be a full, clear, and exact description of the invention, such as will enable others skilled in the art to which it appertains to make and use the same.

The invention relates to wreaths and the method of making the same.

15 The object of the invention is to provide a wreath of cheap and simple construction that will be sufficiently strong and durable to withstand the ordinary handling to which wreaths are subjected, such as packing, shipping, and subsequent use, without undue damage. This object is attained by the novel construction of wreath and method of making the same as hereinafter described and claimed, and as illustrated in the accompanying drawings, in which—

Figure 1 is a side view of a ring of flexible material, such as double-faced corrugated paperboard, which constitutes the frame on which the trimming material is wound, and which, in accordance with my invention, is split transversely thereof to permit of the same being opened for the ready and convenient winding of the ring.

Fig. 2 is an enlarged view of the upper or split portion of the ring with the ends spread apart to open the ring, and showing the method employed in winding a strip of trimming material about the ring by passing the same through the opening between the ends.

Fig. 3 is a view of the same part of the ring after the winding of the same has been completed and showing how the split ends are held together by the winding material.

45 Figs. 4 and 5 are edge and side views, respectively, of the split portion of the ring, showing a modified form of locking means for securing the split ends together.

Figs. 6 and 7 are edge and side views, respectively, of a modified form of frame comprising two superposed rings with a locking member between the same opposite their split ends.

Figs. 8 and 9 are edge and side views, re-

spectively, of a two-ring frame, the rings being arranged with their split joints in staggered relation so that the end of one ring will overlap the joint of the other.

Fig. 10 is an edge view corresponding with that of Fig. 8, but showing the ends spread apart to provide an opening for the passage therebetween of the trimming material in winding the frame.

The invention, in its simplest form, comprises a ring 2 of flexible material, on which is wound a trimming material 3, such as chenille, the ring being transversely split, as at 4, to permit of the same being opened for the convenient and rapid winding of the trimming material thereon.

The ring 2 may be formed of any flexible material that is sufficiently stiff to maintain its form under ordinary handling, and I have found in practice that double-faced corrugated paperboard is particularly well adapted for the purpose in that it is strong, light in weight and cheap.

In making up a wreath, the operative secures one end of the strip of trimming material at some point on the ring, preferably near one side of the split joint, by wrapping the strip one or more times about one of its loose ends, after which the operative will continue the winding operation by passing the strip at each turn or winding thereof between the split ends of the ring as shown in Fig. 2; in this way avoiding the laborious operation of passing the trimming material through the ring at each winding thereof as would be required with the use of a closed ring, and enabling the winding operation to be effected quite as expeditiously as though winding a straight piece or member of any kind.

After the winding operation has been about completed, the ends of the ring are then brought together and the trimming material passed about the same several times to secure them together, by being passed through the closed ring. As a means to more effectually secure together the ends of the ring, I prefer to provide the latter with notches at opposite sides of its split joint, as at 5, 5, in which the trimming material may engage. For example, when the winding operation has been about completed, the strip of trimming material may be engaged in one notch, as at *a* in Fig. 3, from thence

passed across the joint as shown by dotted lines in Fig. 3 and around the ring in a position of engagement with the second notch in the other end of the ring, as at *b*, and thereafter wound around the ring and over its joint several times and finally secured by passing its loose end beneath one or more of its wraps in its usual manner. In this way, it will be clear that the ends of the ring will be securely held together.

The described method of uniting the ends of the ring is sufficient for small wreaths or for those not requiring much handling. In some instances, however, it may be desirable to provide a more positive and rigid connection of the split ends. This I accomplish by providing a locking member *7*, in the form of a segmental strip of cardboard or like material substantially corresponding in width to that of the ring, which is adapted to overlie the split ends of the ring at their joint, as shown in Figs. 4 and 5. This locking member, when bound to the ring by the trimming material, will act to hold the ring ends in alignment and against lateral displacement relatively to each other as will be clear by reference to Fig. 4. Also, by providing said member with notches, such as *8*, *8*, in position for registering with the notches *5*, *5*, in the opposite ends of the ring, the engagement of the strip of trimming material within the several notches will serve to additionally hold the ring ends together by securing them to the locking member *7*. If desired, the locking member may be secured to the ring by means additional to the trimming material, as, for example, by ordinary twine tied around the parts and through the notches therein, as indicated at *9* in Fig. 5. Ordinarily, however, the trimming material alone will be sufficient to effectively secure the parts without the aid of additional fastening means.

In the making of heavier wreaths, I sometimes employ two rings in superposed relation, with the locking member *7* interposed between the same in position opposite their joints, as shown in Figs. 6 and 7. In making up a wreath on a frame of this kind, the same procedure will be followed as before described, that is, the strip of trimming material will be wound about the two rings by passing the same between the ends of the rings until the winding is about completed, at which time the locking member *7* will be placed in position opposite the joints in the ring, after which the winding will be completed and the parts secured together by a further wrapping of the trimming strip about the joints, which is accomplished by passing the strip through the closed rings in usual manner.

In making up a frame with two superposed rings as just described, the split ends

may be secured against lateral displacement by staggering the joints, so that the end of one ring will overlap the joint of the other, as shown in Figs. 8 and 9. With this arrangement of the joints of the two rings, the ends of the latter will be securely held against lateral displacement relatively to each other by the trimming material when the latter is wrapped about said ends. It will be clear by reference to Fig. 10 that such overlapping of the ends of the two rings will not interfere with their being opened to permit of the passing of the trimming material therebetween during the making up or manufacture of the wreath.

It will be understood from the foregoing that wreaths may be manufactured quickly and cheaply in the ways described, and that the wreaths so made will be strong and durable for the purposes intended.

What I claim is:

1. A wreath, comprising a ring of flexible material transversely split at one point, and trimming material wound around said ring and holding the ends thereof together.

2. A wreath, comprising a ring of flexible material transversely split at one point and having shoulders adjacent the split, and trimming material wound around the ring and engaging said shoulders to hold the split ends together.

3. A wreath, comprising a ring of flexible material transversely split at one point and having notches adjacent the split, and trimming material wound around the ring and engaging within its said notches to hold the split ends together.

4. A wreath, comprising a ring of flexible material transversely split at one point, a locking member overlying the split ends, and trimming material wound around the ring and over said locking member to hold the parts together.

5. A wreath, comprising a transversely split ring of flexible material having notches adjacent its split ends, a locking member overlying the split ends and provided with notches registering with the said notches in the ring, and trimming material wound around the ring and overlying locking member and engaging the same within their notches to hold the several parts together.

6. A wreath, comprising a pair of superposed rings, of flexible material each transversely split at one point, said rings being arranged with their ends in overlapping relation, and trimming material wound around said rings and holding the same together.

7. A wreath, comprising a pair of superposed rings of flexible material each transversely split at one point said rings being arranged with their ends in overlapping relation and each having notches adjacent its

split ends, and trimming material wound around the rings and engaging the notches therein to hold the parts together.

8. A wreath, comprising a pair of superposed transversely split rings of flexible material, a locking member between said rings in a position opposite the split ends thereof, and trimming material wound around said rings and holding the parts together.

9. A wreath, comprising a pair of superposed transversely split rings of flexible material each having notches adjacent its split ends, a locking member between said rings in a position opposite the split ends thereof and provided with notches registering with those of the rings, and trimming material wound around said rings and engaging the same and the locking member within their notches to hold the parts together.

10. The method of forming wreaths with rings of flexible material, comprising the transverse splitting of the ring at one point, and then winding the ring with trimming material by passing the same between the split ends of the ring.

11. The method of forming wreaths with rings of flexible material, comprising the transverse splitting of the ring at one point, then winding the ring with trimming material by passing the same between the split ends of the ring, and finally securing the split ends together by passing the trimming material through the ring and about said ends.

12. The method of forming wreaths with

rings of flexible material, comprising the transverse splitting of two rings each at one point, placing the same in superposed relation with the ends of one overlapping those of the other, then winding the rings with trimming material by passing the latter between the split ends of the rings, and finally securing the split overlapping ends together by passing trimming material through the rings and about said ends.

13. The method of forming wreaths with rings of flexible material, comprising the transverse splitting of the ring, partially winding the ring with trimming material by passing the latter between the split ends of the ring, placing a locking member on the ring in position overlying the split ends thereof, and finally passing the trimming material through the ring and about the split ends and overlying locking member to secure said parts together.

14. The method of forming wreaths with rings of flexible material, comprising the transverse splitting of two rings, placing the same in superposed relation, winding said rings with trimming material by passing the latter between the split ends of the rings, placing a locking member on the rings in position overlying the split ends thereof, and finally passing the trimming material through the rings and about the split ends and overlying locking member to secure said parts together.

In testimony whereof I affix my signature.

GILBERT C. WATERS, JR.
